UNITED STATES PATENT OFFICE.

FRANK D. RANDOLPH, OF PLAINFIELD, NEW JERSEY, ASSIGNOR TO THE POTTER PRINTING PRESS COMPANY, OF PLAINFIELD, NEW JERSEY, A CORPORATION OF NEW JERSEY.

SHEET-FEEDING MECHANISM.

1,066,528.

Specification of Letters Patent.

Patented July 8, 1913.

Application filed April 18, 1908. Serial No. 427,876.

To all whom it may concern:

Be it known that I, FRANK D. RANDOLPH, a citizen of the United States, and a resident of Plainfield, in the county of Union and State of New Jersey, have invented certain new and useful Improvements in Sheet-Feeding Mechanism, of which the following is a specification.

The present invention relates generally to sheet feeding and registering devices, and has more particularly reference to a machine for feeding and registering sheets of tin or other material to a printing or other machine.

The invention consists of the following features: In feeding sheets of tin it is somewhat of a problem to obtain good side registering of the sheet owing to the fact that the variations from the standard in the size of individual sheets is considerable, and, frequently, the two side edges of the sheet are not parallel. To overcome this difficulty there is provided a side registering device which is adapted to place the sheet in correct side register and to so maintain it until the sheet is seized by the sheet taking devices on the cylinder. To effect this, the side registering device is adapted to follow the feeding movement of the sheet. In the form here disclosed, the side registering device is given a reciprocating motion both longitudinally and transversely of the sheet, the side registering devices moving transversely away from the sheet substantially at the moment the sheet taking devices seize the sheet, and preferably just after the sheet is so seized. The movement of the side registering device is so timed that as the sheet commences the forward movement, the side registering device travels in the opposite direction and moves inwardly approaching the sheet, then reverses its motion traveling forward with the sheet maintaining it in register and finally recedes from the sheet when the latter is seized by the sheet taking devices. The sheet is given its front register by means of gages carried by the sheet taking devices on the cylinder; and it is therefore important that the side register be maintained until the sheet contacts with the front gages.

Specifically the side registering device consists of a transversely extending carriage forming a guideway, means for reciprocating said carriage longitudinally, and side

gages transversely movable in the said guideway. Suitable means for adjusting these side gages are provided.

Any suitable means may be provided for feeding the sheet forward but preferably a pushing device is arranged which engages with the tail end of the sheet to move it forward over a suitable sheet support. This pushing device is particularly well adapted to advance the sheet properly and to correctly register it when used in connection with the side registering device above described. In the preferred form, this pushing device consists of a reciprocating carriage provided with yieldingly supported upright pusher fingers. Suitable means are provided for adjusting said fingers longitudinally.

In order to accommodate different lengths of sheets, the sheet support is adapted to be lengthened and shortened, and the pushing device is provided with means for varying its position to correspond with the length of the sheet to be fed.

It is advantageous to avoid the necessity of requiring the operator always to place a sheet in the machine at the exact moment the feeding devices are timed to operate. For this purpose there is provided a feed table upon which the sheet may be placed, and means are provided for feeding the sheet so placed upon the feed table onto the sheet support in front of the pushing device at the proper moment. These means may consist, as here shown, of a pair of rotatable rollers adapted to nip the sheet at the proper moment and feed it in. In connection with the foregoing, there may be employed a platform for holding a stack of sheets, adapted to be automatically raised as the sheets are taken off. A convenient arrangement of these features resides in having an auxiliary framework which is adjustable on the main framework and which is adapted to support the feed table, the platform, and the means for feeding the sheet from the feed table to the sheet support. Suitable driving connections are made to operate the means carried by the auxiliary frame, and these driving connections are adjustable to compensate for the adjustment of the auxiliary frame. Likewise the operating mechanism for the pushing device is adjustable. Further, the sheet support is carried at one end on the auxiliary frame.

work and is adapted to be shortened or lengthened by the adjustment of the said framework.

Other features of construction, combination of parts and arrangements of elements 5 will appear as the specification proceeds.

In the accompanying drawings the invention is embodied in a concrete and preferred form but variations may of course be made 10 from the structure shown without departing from the legitimate and intended scope of the invention.

In the said drawings Figure 1 is a general side elevation of a machine embodying the 15 invention. Fig. 2 is a detail view in section of the connection for intermittently raising the stack of tin. Fig. 3 is a transverse vertical sectional view on the line 3—3 of Fig. 1, Fig. 4 is a longitudinal vertical 20 sectional view on the line 4—4 of Fig. 3. Fig. 5 is a perspective view of part of the connection for operating the upper roller on the feed table. Fig. 6 is an enlarged view 25 in side elevation of a portion of the machine shown in Fig. 1. Fig. 7 is a transverse vertical sectional view on the line 7—7 of Fig. 6. Fig. 8 is a vertical sectional view on the line 8—8 of Fig. 9. Fig. 9 is a plan view, 30 partly broken, illustrating the side registering device. Fig. 10 is an end view looking in the direction of the arrow 10 of Fig. 9 partly in section. Fig. 11 is a sectional view 35 on the line 11—11 of Fig. 8. Fig. 12 is a detail view of one end of the impression cylinder, partly in section. Fig. 13 is a sectional view on the line 13—13 of Fig. 12. Fig. 14 is a view similar to Fig. 13, showing 40 the sheet taking device on the cylinder in the act of seizing a sheet. Fig. 15 is a sectional view on the line 15—15 of Fig. 12. Fig. 16 is a sectional view on the line 16—16 45 of Fig. 15. Fig. 17 is a view similar to Figs. 13 and 14, showing the sheet taking device in the act of releasing a sheet.

45 Similar characters of reference indicate corresponding parts in different views.

1 indicates the main framework for properly supporting the parts comprising the machine.

50 The invention is here shown associated with a printing machine of a well known type. It is to be understood, however, that the sheet feeding and registering devices may be used in connection with other apparatus for acting upon the sheets fed.

55 The printing machine here disclosed consists of an impression cylinder 2, a transfer cylinder 3 having the rubber off-set blanket 4, and the plate or type cylinder 5.

60 The side registering device is constructed as follows: 35 denotes a suitable sheet support in front of the printing machine. 63 indicates a transversely extending carriage, having a guideway 64 extending trans- 65 versely of the machine, and adapted to slide

in the longitudinal guides 65 on the framework. This carriage 63 is given a reciprocating motion longitudinally of the machine by means of the cam 66 operating the levers 67 connected to the said carriage and mounted on the shaft 68. The motion is transferred from the cam 66 to the shaft 68 by means of the roll 69 mounted on the arm 70. Sliding in the guideway 64 are two oppositely moving members 71. Each of these 75 members 71 is provided with a cam roll 72 engaging in the fixed cam slots 73 on the framework so that as the carriage 63 reciprocates the members 71 will reciprocate transversely back and forth. Mounted upon 80 the said members 71 are the members 74 which can be adjusted to different positions transversely of the machine by means of the thumb screws 75 adapted to engage with the holes 76. Two side gages 77 and 78 85 are mounted on the members 74. One of the said gages is held unyieldingly but adjustably on one member 74 by means of the threaded connection 79. This connection is threaded in opposite directions and engages with one end in the member 74 and with its other end in the member 77. The gage member 78 is held yieldingly by means of the spring 80 which is interposed between the adjusting screw 81 carried by 95 the member 78 and the member 74.

The impression cylinder is provided with suitable sheet taking devices such as the grippers 82 mounted on the gripper rod 83 in the cylinder and normally held in their 100 closed positions by means of the spring 84 in a well known manner. These grippers are adapted to be opened by means of the cam 85 which is here shown as being loosely mounted on a concentric portion 86 of one 105 of the eccentric bushings 7 of the said impression cylinder. To prevent the said cam from following the turning movement of the bushings 7 when the cylinder is tripped, there is provided a link 87 by means of 110 which the said cam is secured to the framework 1. The motion from the cam 85 is imparted to the grippers by means of the cam roll 88 carried by the gripper rod. The cam 85 is so timed that the sheet is seized at the 115 feeding point of the cylinder and is carried through between the cylinders until the point shown in Fig. 17 is reached, when a sufficient amount of the sheet has been carried through to prevent it from sticking to 120 the blanket on the transfer cylinder. The grippers are now opened and the sheet drops on to the conveyer 89. Mounted on the grippers 82 are the front gages 90 held in position by means of the set screws 91 passing 125 through the slot 92 of the said gages and adjustable by means of the screws 93. Each gripper will usually be provided with one of these front gages, but in order to register the sheet properly two of these front gages 130

only will be used, the rest being drawn back or otherwise disconnected.

101 indicates a pushing device adapted to engage with the tail end of the sheet on the sheet support 35 to advance it toward the cylinders of the printing machine. This pushing device slides on two rods 102 arranged longitudinally of the machine and consists of a carriage having bushings 103 connected by means of transverse rods 104. 5 Mounted upon one of these transverse rods are upright pusher fingers 105 extending up through the sheet support 35.

The fingers 105 are held in their upright position by means of the threaded rods 106 passing through the sleeves 107 and are adjustable in the said sleeves by means of the nuts 108. A coiled spring 109 surrounds each of the rods 106, the tension of which can be adjusted by means of the threaded sleeve 110. The carriage of the pushing device is provided with longitudinal slots 111 in which the links 112 can be adjusted by means of the set screws 113. These links are 20 connected with the levers 114 mounted on the shaft 115 which is rocked by means of the arm 116 carrying the roll 117 engaging with the cam 118.

The sheet support 35 consists of strippers 30 119 and 120 which overlap each other as shown, and which are supported at one end on the bracket 121 carried by the framework and with its other end on the brackets 122 carried by the auxiliary framework 123. 35 The brackets 121 and 122 are adjustable transversely by means of the set screws 124 and 125.

As the sheet advances under the influence of the pushing device, the side registering 40 device moves in the opposite direction and approaches the sheet transversely. The side registering device now reverses its motion and moves in the same direction as the sheet maintaining it in register. As the front 45 edge of the sheet comes in contact with the front gages, carried by the grippers on the impression cylinder, it receives its front register and is then seized by the grippers. Substantially at this moment the side registering device recedes transversely while the pushing device returns to its original position.

The side registering device now preferably remains in this forward and separated 55 position (the cam roll 69 being then in engagement with the concentric portion of the cam 66, substantially as shown in Fig. 1, and the rolls 72, resting then in the forward angular ends of the cam slots 73) until the 60 next sheet is about to be fed forward. As the next sheet is fed forward, the cam 66 has turned so that the throw thereof actuates the cam roll 69, thereby causing the carriage 63 to advance toward the approaching sheet 65 and the rolls 72, due to their engagement

with the inclined portion of the slots 73, cause the side gages to approach and engage the opposite edges of the sheet (substantially the position illustrated in Fig. 9). The side registering device continues to 70 move in the direction opposite to the travel of the sheet, until the rolls 72 reach the end of the straight portion of the cam slot 73. At this time the cam roll 69 is substantially 75 in the lowest part of the depression in the cam 66. As the cam continues to revolve, the cam roll rides up to the concentric portion of the cam, whereby the forward throw is given to the side registering device. During this forward throw, the side registering 80 device moves at substantially the same speed as the forward advancing movement of the sheet, and the rolls 72 engaging in the inclined portion of the slots, cause the side gages to be spread, substantially at the 85 moment the forward end of the sheet is gripped by the sheet taking devices.

The auxiliary framework 123 is slidably mounted in the main framework and can be adjusted by means of the gear 126 carried by the said auxiliary framework engaging with the rack 127 in the main framework. By adjusting the auxiliary framework the sheet path 35 is lengthened or shortened to correspond to different lengths 95 of sheets. To vary the position of the pushing device the set screws 113 are adjusted in the slots 111.

The auxiliary framework carries a feed table 128 having the guides 129 and provided with a pair of rollers 130 and 131, which are geared together as shown, and the latter of which is pivotally supported on the shaft 132 so that it may be raised and lowered into contact with the roller 130. 133 105 indicates a cam acting upon the roll 134 carried by the arm 135 mounted on the bushing 136 seated loosely on the stud 137 in the end of the shaft 115. Connected to this bushing is the rod 138 having a slotted connection 110 139 with the arm 140 of the roller 131. When a sheet is placed upon the feed table 128 between the guides 129 and on the roller 130, then, upon the descent of the roller 131, the sheet will be fed out onto the sheet support 35 in front of the pushing device.

Adjacent to the feed table is a platform 141 adapted to hold a stack of sheets 142. This platform is automatically raised by means of the screws 143 operated by the 120 bevel gears 144 meshing with the bevel gears 145 on the transverse shaft 146. This shaft carries a ratchet 147 with which engages the pawl 148 pivoted at 149 and actuated by the rod 150 connected to the lever 114. The rod 150 passes through the bushing 151 carried by the lever 114 and is adjustably secured thereto by means of the set screw 152, so as to operate the pawl 148 in harmony with 125 the other parts of the feeding mechanism. 132

If the auxiliary framework is adjusted, the connection 150 is likewise adjusted to correspond therewith. In practice, the operator will stand behind the platform 141 and place the sheets one by one on the feed table and on the lower roller 130. The operation of the machine will then cause the sheet to be automatically fed forward and printed.

Any suitable gearing may be employed to transmit motion to the various parts. In the present instance, the gearing is as follows:—From the driving pulley 153 the motion is transmitted through the pinion 154 to the intermediate gear 155 on the stud 156. The stud 156 also carries the pinion 157 engaging with the gear 158 on the impression cylinder, and with the gear 159 from which latter motion is transmitted to the gear 160 on the cam shaft 15. From the impression cylinder the other cylinders of the printing couple are driven in the usual way. Gear 158 also imparts motion to the conveyer 89 by means of the pinions 161 and 162. The gear 155 also meshes with the pinion 163 which in turn drives the pinion 164 in mesh with the gear 165 on the stud 166. The stud 166 carries the bevel gear 167 meshing with the bevel gear 168 on the longitudinally extending shaft 169. Mounted on the shaft 169 is the bevel gear 170 adapted to slide thereon by means of the spline 171 so as to compensate for the adjustment of the auxiliary framework. Meshing with the gear 170 is the bevel gear 172 moving with the gear 173 on the roller 130. With the gear 173 meshes the pinion 174 on the roller 131.

What is claimed is:

1. The combination of means for feeding a sheet, a side registering device mounted independent of the sheet feeding means, and operating means for the side registering device adapted to cause the same to reciprocate longitudinally during the feeding movement of the sheet, and to reciprocate transversely so as to engage the side edges of the sheet during the longitudinal reciprocating movement of the same.

2. The combination of a cylinder, sheet taking devices on said cylinder, means for feeding the sheet into the bite of the sheet taking devices, side gages adapted to follow the movement of the sheet feeding means, and means for moving the side gages transversely away from the sheet substantially at the moment the sheet taking devices seize the sheet.

3. The combination of a cylinder, sheet taking devices on said cylinder, means for feeding the sheet into the bite of the sheet taking devices, side gages having a combined longitudinal and transverse reciprocating movement, said side gages receding from the sheet substantially at the moment the sheet taking devices seize the sheet.

4. The combination of means for feeding a sheet, side gages adapted to engage with the sides of the sheet, and operating means for said side gages adapted to cause the said gages to travel inwardly and, simultaneously therewith, in a direction opposite that of the feeding movement of the sheet, then in a straight direction opposite to the feeding movement of the sheet, then in the same direction as the feeding movement of the sheet in a straight line, and then outwardly away from the sheet and in a direction following the feeding movement of the sheet.

5. The combination of means for engaging with the tail end of the sheet to push it forward, side gages adapted to engage with the sides of the sheet, and operating means for said side gages adapted to cause the said gages to travel inwardly and, simultaneously therewith, in a direction opposite that of the feeding movement of the sheet, then in a straight direction opposite to the feeding movement of the sheet, then in the same direction as the feeding movement of the sheet in a straight line, and then outwardly away from the sheet and in a direction following the feeding movement of the sheet.

6. The combination of a cylinder, sheet taking devices on said cylinder, means for feeding a sheet forward into the bite of the sheet taking devices, a side registering device, means for imparting a combined longitudinal and transverse reciprocating movement to the side registering device so timed that as the sheet commences its forward movement, the side registering device travels in the opposite direction and moves inwardly approaching the sheet, then reverses its motion traveling forward with the sheet maintaining it in register and finally recedes from the sheet substantially at the moment it is seized by the sheet taking devices.

7. The combination of a cylinder, sheet taking devices on said cylinder, front registering devices carried by the sheet taking devices, means for feeding the sheet against the front registering devices and into the bite of the sheet taking devices, a side registering device adapted to follow the movement of the sheet feeding means, and means for moving the side registering device transversely away from the sheet substantially at the moment the latter contacts with the front registering device and is seized by the sheet taking device.

8. The combination of a cylinder, sheet taking devices on said cylinder, front registering devices carried by the sheet taking devices, means for feeding the sheet against the front registering devices and into the bite of the sheet taking devices, and a side registering device having a combined longitudinal and transverse reciprocating move-

- ment, the side registering device receding from the sheet substantially at the moment the sheet contacts with the front registering device and is seized by the sheet taking device. 5
9. The combination of a cylinder, sheet taking devices on said cylinder, front registering devices carried by the sheet taking devices, means for feeding the sheet against the front registering devices and into the bite of the sheet taking devices, a side registering device, means for imparting a combined longitudinal and transverse reciprocating movement to the side registering device so timed that as the sheet commences its forward movement the side registering device travels in the opposite direction and moves inwardly approaching the sheet, then reverses its motion traveling forward with the sheet maintaining it in register, and finally recedes from the sheet substantially at the moment it contacts with the front registering device and is seized by the sheet taking device. 10
10. A side registering device comprising a transversely extending carriage forming a guideway, means for reciprocating said carriage longitudinally, side gages slidably mounted in said guideway, and means for reciprocating said gages transversely. 15
11. A side registering device comprising a transversely extending carriage forming a guideway, means for reciprocating said carriage longitudinally, oppositely sliding members in said guideway, means for reciprocating said members transversely, and gages adjustably mounted on said members. 20
12. A side registering device comprising a transversely extending carriage forming a guideway, means for reciprocating said carriage longitudinally, oppositely sliding members in said guideway, means for reciprocating said members transversely, a gage adjustably secured to one of said members, and a gage, having an independent transverse yielding movement, secured to the said other member. 25
13. The combination of a sheet support, a pushing device adapted to engage with the tail end of the sheet to move it forward, a side registering device, and means for imparting a combined longitudinal and transverse reciprocating movement to the side registering device, so timed that as the sheet advances under the influence of the pushing device the side registering device travels in the opposite direction and moves inwardly approaching the sheet, then reverses its motion traveling forward with the sheet maintaining it in register and finally recedes from the sheet substantially at the moment the pushing device comes to the end of its motion. 30
14. The combination of a sheet support, a pushing device adapted to engage with the tail end of a sheet on the support, a feed table, means for feeding a sheet from the feed table to the sheet support, a platform for holding a stack of sheets adapted to be intermittently raised, and driving mechanism for operating the pushing device, the means for feeding the sheet from the table and for raising the platform, timed to operate in proper sequence. 35
15. The combination of a main framework, an auxiliary framework adjustable on the main framework, a sheet support, carried at one end on the main framework and at its other end on the auxiliary framework, adjustable with the auxiliary framework to vary its length, a pushing device for engaging with the tail end of a sheet on the support, means for operating said pushing device having a constant stroke and means for varying the position of the pushing device according to the length of the support. 40
16. The combination of a main framework, an auxiliary framework adjustable on the main framework, a sheet support, carried at one end on the main framework, and at its other end on the auxiliary framework, adjustable with the auxiliary framework to vary its length, a pushing device for engaging with the tail end of a sheet on the support, means for operating said pushing device having a constant stroke and means for varying the position of the pushing device according to the length of the support, a feed table carried by the auxiliary framework, means for feeding a sheet from the feed table onto the sheet support, a platform for holding a stack of sheets adapted to be intermittently raised, also carried by the auxiliary framework, and driving connections for operating the means for feeding a sheet from the table to the support and for raising the platform adjustable to correspond to the position of the auxiliary framework. 45
17. In combination with sheet feeding means, a side registering device comprising a carriage having a bodily reciprocating movement, side gages carried by said carriage, and means for imparting to the side gages a transversely reciprocating movement on the carriage. 50
18. Sheet feeding mechanism comprising, pusher fingers, a carriage, means for imparting a longitudinal reciprocating motion to said carriage, side gages movable transversely on the said carriage, and means for imparting a transverse reciprocating movement to the side gages as the carriage is reciprocated longitudinally. 55
19. A side registering device comprising, a carriage, means for imparting a reciprocating movement to said carriage, members slidably mounted on said carriage, side gages carried by said members, cam rolls 60

on the outer ends of said members, and members having cam slots adapted for engagement by said cam rolls for imparting an independent movement to the sliding members during the bodily reciprocation of the carriage.

20. Sheet feeding mechanism comprising sheet advancing means for engaging the rear edge of the sheet to advance the same, 10 side gages mounted independently of the sheet advancing means, and means for moving said side gages in opposite directions into engagement with the opposite side

edges of the sheet, substantially at right angles to the movement of the sheet advancing means, the said side gages also having a longitudinal movement corresponding to the feeding movement of the sheet advancing means.

Signed at Plainfield, in the county of Union and State of New Jersey this 16th day of April A. D. 1908.

FRANK D. RANDOLPH.
